SPARK-PLUG.

1,085,024.

Specification of Letters Patent. Patented Jan. 20, 1914.

Application filed August 21, 1911. Serial No. 645,082.

To all whom it may concern:

Be it known that I, ADOLFO DE CLAIRMONT, citizen of the United States, residing at Toledo, in the county of Lucas and State of Ohio, have invented certain new and useful Improvements in Spark-Plugs, of which the following is a specification.

This invention has for its primary object a simple, durable and efficient construction 10 of spark plug for internal combustion engines, which will be positive in its action, and practically self-cleaning and not liable to get out of order, and the invention consists in certain constructions and arrangements of the parts that I shall hereinafter 15 fully describe and claim.

For a full understanding of the invention, reference is to be had to the following description and accompanying drawings, in 20 which:

Figure 1 is a side elevation of my improved spark plug; Fig. 2 is a longitudinal sectional view thereof; and, Fig. 3 is an end view.

25 Corresponding and like parts are referred to in the following description and indicated in all the views of the drawings by the same reference characters.

Referring to the drawing, the numeral 1 30 designates the metallic body portion of my improved spark plug, formed at one end with exterior screw threads for attachment to an engine cylinder and formed in its opposite end with interior screw threads 35 designed for engagement by a screw threaded bushing 2 which is adapted to clamp, in the body portion 1, a core 3 of porcelain, mica or some equivalent insulating substance. Projecting from the inner end of 40 the body portion 1 and preferably formed integral therewith, are a plurality of electrodes 4 which are disposed substantially in a longitudinal alinement with the main body portion of the plug and which are formed 45 at their free extremities with slightly in-turned points 5, as best illustrated in Fig. 3. There are four of these electrodes in the present embodiment of the invention, spaced in equidistant relation to each other, and 50 within the circle of these points or electrodes 4 and almost entirely out of the plane thereof and wholly without and spaced from the body portion 1, a ball or spherical electrode 6 is positioned, being spaced from the 55 extremities 5 of the electrodes 4, as is evi-

dent and being held on the inner end of a rod 7 which is mounted in the core 3. The ball 6 may be formed of any suitable substance, such as platinum, steel, etc., and the co-acting electrodes 4 may also be formed of 60 any of these or other suitable substances. The rod 7 is provided at its outer end with the ordinary binding nut 8.

For a purpose to be later described the upper end of the rod 7 passes through a 65 sleeve 9 which loosely encircles the upper end of the rod, and is held from any longitudinal movement relative thereto. This sleeve permits the rod to be rotated within the sleeve. The exterior of the sleeve is 70 screw threaded and engages with the internal screw threads on a nut 8. It will be seen that by rotating the nut 8 that the rod may be raised or lowered but that the rotation of this nut 8 will not act to rotate the rod and 75 that a rotation of the rod 7 will not act to rotate the sleeve 9 and therefore shift the rod 7 longitudinally. The rod 7 is also screw threaded intermediate its ends and provided with the nut 10, which forms a 80 stop for engaging the end wall of the recess in the lower end of the core. It will be noted from Fig. 6 that this recess is of greater diameter than the stop nut 10 and hence does not act to impede the rotation of 85 this stop nut. Inasmuch as the nut 10 is adjustable upon the rod 7, it will hold the rod in a proper adjusted position against any accidental vertical displacement, so that the ball 6 will come in proper relation to the 90 terminals 5. Of course, the nut 8 limits any downward movement of the rod 7 and with the nut 9 holds the rod in its longitudinal adjusted position.

It will be seen that I have provided means 95 therefore, whereby the rod 7 may be longitudinally adjusted and held in this adjusted position from any vertical movement. It will further be seen that the rod 7 may be 100 rotatably shifted so as to bring a fresh portion of the ball 6 opposite the points 5. This may be done by hand but it will be obvious that the oscillations of the machine will tend to jar the plug and further cause a slight jarring movement of the ball which will 105 tend to rotate. Of course the nut 8 may be turned up so tightly as to draw the stop nut 9 firmly against the upper wall of the recess in the core and hold the rod from any rotary movement. By loosening up upon the nut 8, 110

- however, so as to permit the nut 10 to move away from the end of the recess, the rod 7 may be readily rotated by means of the pliers engaged with the projecting end of the rod 7 or the nut 8 left in such position as will limit the vertical movement of the rod 7 within very short bounds, but at the same time leave the rod 7 free to turn by the jar of the machine.
- 10 It will be particularly noted that the ball 6 is entirely outside of the body portion 1 of the plug and is exposed upon all sides to the gas, free gas space being formed all around the ball and in the space between the 15 same and the inwardly projecting substantially parallel electrodes or points 4. By thus exposing the electrodes entirely to the compressed gases, the same will be exploded without failure.

20 Having thus described the invention, what is claimed as new is:

1. A spark plug comprising a body portion provided at its inner end with an inwardly projecting electrode, a core in said body portion, a rod within the core and adapted to have free longitudinal movement therein, an adjustable stop mounted near the lower end of the rod and engageable with the lower end of the core, an exteriorly 25 screw-threaded sleeve surrounding the upper end of the rod above the core and having swiveled engagement with the rod for free rotation thereon, and a nut engaging the sleeve and bearing against the upper 30 end of the core.

2. A spark plug comprising a body portion provided at its inner end with an inwardly projecting electrode, a rod extending loosely through the body portion and 40 having free rotary movement and free longitudinal movement therein, a ball electrode supported on the lower end of the rod adjacent the first named electrode, and means for adjusting the rod longitudinally but permitting the rod to have free independent 45 rotation without change of longitudinal position.

3. A spark plug comprising a body provided at its inner end with an inwardly projecting electrode, a rod loosely disposed within said body for free rotary movement, that portion of the rod disposed within said body being smooth to provide for longitudinal movement of the rod, a ball electrode 50 on the lower end of the rod adjacent the first-named electrode, and means for adjusting the rod longitudinally with relation to

the body, said means permitting the rod to have free independent rotation without change of longitudinal position.

4. A spark plug comprising a body portion provided at its inner end with a plurality of inwardly projecting electrodes, the space around and between said electrodes being entirely open, an insulating core within 65 said body portion, a rod rotatable in and extending loosely through the core and longitudinally adjustable therein, said rod being screw threaded intermediate its ends, a screw threaded sleeve loosely surrounding 70 the upper end of the rod, said sleeve having swiveled engagement with the rod, an adjusting nut upon the upper end of the rod engaging the sleeve and bearing against the upper end of the core, an adjusting nut upon 75 the screw threads intermediate the ends of the rod and engaging the inner ends of the core, and a ball secured to the inner end of the rod outside of and spaced from the body portion and within the circle defined by the 80 free extremities of said electrodes and spaced therefrom, the inner end of the body portion being open around the ball to a diameter greater than the diameter of the ball.

5. A spark plug comprising a body portion provided at its inner end with an inwardly projecting electrode, a rod loosely disposed in said body for free rotary movement and for longitudinal movement independent of its rotary movement, a ball electrode supported on the lower end of the rod opposite the point of the first named electrode, means for longitudinally adjusting the rod, and means for clamping the rod in any longitudinally adjusted position.

6. A spark plug comprising a body provided at its inner end with a plurality of inwardly projecting electrodes, a smooth rod loosely disposed within the body for free rotary movement therein and free longitudinal movement therein, a spherical electrode carried upon the lower end of the rod, a screw-threaded sleeve swiveled upon the upper end of the rod to permit the rod to have free turning movement therein, and a 105 nut engaging the said sleeve whereby the rod may be adjusted longitudinally without impeding its free rotation.

In testimony whereof, I affix my signature in presence of two witnesses.
